US00D865723S

(12) **United States Design Patent** (10) Patent No.: **US D865,723 S**
(45) Date of Patent: **** Nov. 5, 2019**

(54) **ARRAY MICROPHONE ASSEMBLY**

- (71) Applicant: **Shure Acquisition Holdings, Inc.**, Niles, IL (US)
- (72) Inventors: **Elizabeth Ahra Cho**, Wilmette, IL (US); **Gregory William Lantz**, Aurora, IL (US); **John Matthew Miller**, Grayslake, IL (US)
- (73) Assignee: **Shure Acquisition Holdings, Inc.**, Niles, IL (US)
- (**) Term: **15 Years**
- (21) Appl. No.: **29/700,875**
- (22) Filed: **Aug. 6, 2019**

Related U.S. Application Data

CLAIM

The ornamental design for an array microphone assembly, as shown and described.

DESCRIPTION

FIG. 1 is a front, top, right perspective view of an array microphone assembly, showing the new design; FIG. 2 is a rear, bottom, left perspective thereof; FIG. 3 is a top plan view thereof; FIG. 4 is a bottom plan view thereof; FIG. 5 is a front view thereof; and, FIG. 6 is a left side view thereof.

The broken lines of even length shown in the drawings illustrate portions of the array microphone assembly that form no part of the claimed design.

1 Claim, 5 Drawing Sheets
